FOOD WARMER OVEN

Robert G. Wilson, 643 E. Faris Road, Greenville, S.C.

Filed Aug. 3, 1964, Ser. No. 81,144

Term of patent 14 years

(Cl. D81—10)

Fig. 1.

Fig. 2.

I claim:

The ornamental design for a food warmer oven, substantially as shown.
